(57) **CLAIM**

The ornamental design for a ceiling fan housing, as shown and described.

DESCRIPTION

FIG. 1 is a perspective view from below of a ceiling fan housing in accordance with my design, including the environment thereof;

FIG. 2 is a greatly enlarged perspective view from below of the ceiling fan housing in accordance with my design, including the environment thereof;

FIG. 3 is a greatly enlarged perspective view from above of the ceiling fan housing in accordance with my design, including the environment thereof;

FIG. 4 is a greatly enlarged side elevation view of the ceiling fan housing in accordance with my design, including the environment thereof;

FIG. 5 is an enlarged bottom plan view of the ceiling fan housing in accordance with my design; and,

FIG. 6 is an enlarged top plan view of the ceiling fan housing in accordance with my design.

The broken lines showing environmental structure are for illustrative purposes and form no part of the claimed design.
